US0D1071990S

(12) United States Design Patent (10) Patent No.: US D1,071,990 S
(45) Date of Patent: * Apr. 22, 2025

(54) DISPLAY SCREEN OR PORTION THEREOF
WITH A GRAPHICAL USER INTERFACE

(71) Applicant: Aristocrat Technologies, Inc., Las Vegas, NV (US)

(72) Inventors: Britta Nauta-Larsen, Reno, NV (US); John Ludwick, Reno, NV (US)

(73) Assignee: Aristocrat Technologies, Inc., Las Vegas, NV (US)

() Term: 15 Years

(21) Appl. No.: 29/929,238

(22) Filed: Feb. 20, 2024

Related U.S. Application Data

(63) Continuation of application No. 29/915,104, filed on Oct. 25, 2023, now Pat. No. Des. 1,021,936, which is a continuation of application No. 29/828,739, filed on Feb. 28, 2022, now Pat. No. Des. 1,009,076.

(57) CLAIM

The ornamental design for a display screen or portion thereof with a graphical user interface, as shown and described.

DESCRIPTION

The FIGURE is a front view of a display screen or portion thereof with a graphical user interface according to the new design.

The outermost broken line in the FIGURE illustrates a display screen or portion thereof and forms no part of the claimed design. The remaining broken lines represent elements of the display screen or portion thereof with a graphical user interface that form no part of the claimed design.
